VARIABLE FILTERING AND TIMING
METHOD AND SYSTEMRobert L. Haynes, Indianapolis, Ind., assignor to
Radio Corporation of America, a corporation
of Delaware

Application September 1, 1943, Serial No. 500,809

14 Claims. (Cl. 179—100.3)

This invention relates to electrical current transmission systems and particularly to an electronic control circuit providing variable filtering and timing characteristics for electrical transmission systems in which a current corresponding to the amplitude of a signal is utilized for controlling the transmission characteristics such as the gain of the system, or for controlling auxiliary equipment operating in conjunction with the transmission system.

In the recording of sound for motion pictures, the sound currents are transmitted from a pickup device, such as a microphone, to a recorder wherein a light beam is normally varied in accordance with the instantaneous values of the sound waves. It is well-known that in such systems a portion of the sound currents are rectified and filtered and then impressed on a noise reduction device such as light intercepting shutters or on the instantaneous light modulator itself. It is also well-known that in various transmission circuits, such as those used for sound recording, radio broadcasts, and public address systems, that devices known as compressors and expanders are employed to vary the ratio or range of amplitudes of the signal before recording or reproduction.

In all the above-mentioned systems, some form of rectifier is employed for obtaining a unidirectional current which varies with the amplitude of the signal. Also, the use of a rectifier generally necessitates the use of a filter between the rectifier and its load regardless of whether the load is a mechanical device, such as a shutter in a noise reduction unit, or a resistance for varying the grid bias of an amplifier to control the gain thereof. Such filters include condensers and resistances and, as is well understood, the better the filtering obtained, the slower the timing and vice versa. Usually, therefore, it is necessary to reach a compromise between the optimum amount of filtering and the optimum timing characteristic, since when the timing is too slow, distortion is introduced in the form of "peak clipping" of the sound waves, and when a small amount of filtering is used to obtain fast timing, distortion is introduced in the form of flutter or spurious frequencies from the rectifier.

The present invention is directed to an electronic impedance control which varies in accordance with the character of the signal; that is, the discharge rate of the filter condenser is made slow providing good filtering during crescendos and steady tones, at which periods fast timing is neither necessary nor desirable, while a fast discharge is obtained at times when the signal am-

plitude diminishes rapidly or ceases suddenly. In other words, the discharge rate can be automatically controlled in such a way as to vary the filtering characteristic according to the nature of the signal. Another feature of the invention is that no tube need be operated with its cathode floating on a high impedance circuit which makes the system reliable because leakage currents between the heater and cathode are prevented.

10 The principal object of the present invention, therefore, is to improve the filtering of rectified alternating currents for control purposes.

Another object of the invention is to improve the rectification and filtering of alternating currents used for control purposes.

15 A further object of the invention is to automatically vary the discharge rate of a filter condenser in accordance with the nature of a signal current.

Another object of the invention is to provide an 20 automatic control from the output of a rectifier for varying the timing and filter characteristic of the rectifier filter.

Another object of the invention is to vary the 25 filtering of all rectified currents in accordance with the variation in amplitude of the signal being rectified.

Although the novel features which are believed 30 to be characteristic of this invention will be pointed out with particularity in the appended claims, the manner of its organization and the mode of its operation will be better understood by referring to the following description read in conjunction with the accompanying drawing forming a part hereof, in which:

35 Fig. 1 is a schematic circuit diagram illustrating the basic principles of the invention.

Fig. 2 is a schematic circuit diagram illustrating a complete control circuit embodying the invention, and,

40 Fig. 3 is a schematic circuit diagram showing a modification of the portion of the circuit of Fig. 2 to the right of the dotted line.

Referring now to Fig. 1, the signal to be rectified, which may be a signal being recorded or 45 one being transmitted by a public address or radio broadcast system, is impressed upon the primary of transformer 5 connected to terminals 6. The signal is rectified in a rectifier 8 connected in series with the secondary of the 50 transformer 5. The rectified impulses are filtered by condensers 10 and 11 and resistance 12, condenser 10 being the principal timing control, while condenser 11 and resistance 12 are the usual type of filter elements whose effect is negligible upon the timing. In the usual type of

timing filter, a resistance is shunted across condenser 10 to control its discharge rate. In the present system, the remainder of the circuit of Fig. 1 has been substituted for the normal shunting resistance and this portion of the circuit will now be described.

Connected across terminals 14 is a 180-volt direct current energy source, the upper terminal of which is connected to the upper terminal of the condenser 10 over resistances 16, 17, 18, and 19, while in shunt to this energy supply is a rectifier 21 and a pair of controlled impedance vacuum tubes 22 and 23, the impedance of which may be varied by varying the potential connected across terminals 25. When no zero bias is applied across terminals 25, the plate voltage of these tubes falls practically to zero due to the low impedance thereof, the voltage of the source being expended across resistors 16 and 17. This makes point X at substantially ground potential. If only one controlled impedance tube is used such as tube 23 alone, the potential of point X might not be reduced to a low enough value to give satisfactory operation on low amplitude signals. By using two tubes and the additional resistor 17, the point X is made to approach much more closely to zero. Thus, with no bias on tubes 22 and 23, the effective resistance in shunt to condenser 10 is that provided by resistors 18 and 19 in series, the values of these resistors, for purposes of illustration, being 9 and 1 megohms, respectively. No current will flow through rectifier 21 because its plate voltage is negative. Since the effective resistance across condenser 10 is 10 megohms, the rate of discharge, therefore, will be slow and good filtering obtained.

To obtain a fast discharge of condenser 10, the tubes 22 and 23 are operated at cut-off bias which increases the impedance of the tubes and their plate potential rises to substantially 180 volts positive. Under these conditions, a current of substantially 20 micro-amperes flows through resistors 16, 17, and 18 to point Y. When no alternating current signal is present across terminals 6, the full 20 micro-amperes goes through tube 21 to ground. When an audio signal of 20 volts peak across the secondary of transformer 5 is present, the entire 20 micro-amperes is used as discharge current through resistor 19, thus providing a rapid discharge of the condenser 10 as compared with the discharge rate when both resistors 18 and 19 are in shunt thereto. At intermediate values of signal voltage, the current divides between tube 21 and resistor 18 and regardless of the signal level, provided it does not exceed 20 volts, point Y remains at ground potential, and the effective resistance across condenser 10 is 1 megohm.

Thus, the circuit of Fig. 1 may be operated either with normal timing, which is obtained when the one megohm resistor 19 is in shunt to condenser 10, or with slow discharge timing, which is obtained when the 10 megohms of resistor 18 and 19 in series are in shunt to condenser 10. It will be noted that in this circuit all cathodes of the vacuum tubes are grounded, thus eliminating any floating cathodes to make the system unstable due to leakage currents between the heaters and cathodes of the respective tubes.

Since it has been shown that the discharge rate of the condenser 10 may be varied by changing the potential across terminals 25, ref-

erence is now made to Fig. 2 wherein the timing and filtering characteristics are automatically modified or varied by the signal in accordance with the nature of the signal. An automatic control circuit is employed in which the quality of the filtering controls the timing. It will be noted that the portions of Figs. 1 and 2 to the right of the dotted line in each figure are identical, except for the conductor 27 connecting the point Z through condenser 28 to the input of an amplifier 29. Also, the voltage across terminals 14 is now made 250 volts instead of 180 volts as in Fig. 1. In the systems of Figs. 1 and 2, the output voltage of the rectifier 8 contains a certain amount of ripple, the amount of ripple depending, at any instant, upon the nature of the signal. Now, it has been found, in operating noise reduction equipment, that, at times when the audio system is such as to produce a large amount of ripple (continued low frequency tones, and crescendos) fast timing is neither necessary nor desirable, and a real improvement in filtering is obtained by using a slow rate of discharge at these times. Fast timing is required only at times when the signal amplitude diminishes rapidly or ceases suddenly, at which time no ripple is present at point Z. The circuit of Fig. 2 automatically produces a slow discharge when ripple is present and a fast discharge when the ripple is absent.

This control is accomplished by feeding the ripple into amplifier 29 over a transformer 31 through a rectifier 32, through a direct current amplifier 33 to tube 34. A filter system is provided comprising a condenser 36 and a resistor 37, intermediate rectifier 32 and amplifier 33, to provide a slow rate of change from slow to fast timing, condenser 36 and resistance 37 having a large time constant, which causes a slow timing condition to be maintained continuously, even when the ripple signal consists of short frequent pulses instead of a steady signal.

When no signal is present at point Z, tube 34 is biased to cut-off by a battery 40 or other suitable source of potential and fast timing results. As explained in connection with Fig. 1, when cut-off bias is placed on tube 34, the tube has a high impedance and only resistor 19 is effectively in shunt to condenser 10. When ripple is present, the output of the amplifier 33, flowing through resistance 41, shifts the grid voltage of tube 34 positive so that tube 34 operates without bias, and slow timing results, since both resistors 18 and 19 are now in shunt to condenser 10.

In the operation of this circuit with zero bias, the plate-cathode voltage drop across the tube 34 is not zero, but is between 20 and 30 volts, depending upon the circuit constants. In order to cause the plate potential of tube 34 to fall to zero bias, the bias voltage of source 40 is made equal to the zero bias plate-cathode drop in tube 34, the batteries 40 and 42 being connected as shown.

Referring now to Fig. 3 in which a modification of the circuit of Fig. 2 to the right of the dotted line is shown, this modification avoids a possible disadvantage of the circuit of Fig. 2. Under certain circumstances, the automatic control of filtering in the circuit of Fig. 2 may not be as effective as desired due to the fact that when the ripple signal is obtained as shown in Fig. 2, the improved filtering resulting from producing slow discharge timing may reduce the ripple to such an extent that an insufficient ripple signal is available to activate the control circuit. This diffi-

culty is avoided with the modification shown in Fig. 3, by providing a separate rectifier and filter circuit which is not controlled by the feedback system. Therefore, in addition to the rectifier tube 8 connected to the secondary of transformer 5, a second rectifier 44 is also connected to transformer 5 along with its timing circuit of condenser 45 and resistor 46, this rectifier, condenser, and resistor not benefiting from the improved filtering obtained in the main amplifier circuit. This auxiliary circuit has fast timing at all times, thereby providing ample ripple signal for the control circuit.

Thus, the above system will provide from any alternating current signal varying in amplitude impressed across terminals 6, a high quality unidirectional control current corresponding to the variations in amplitude of the signal for controlling noise reduction elements or the gain of a compressor or expander. High quality is obtained by automatically securing slow timing during crescendos and low frequency tones to increase the filtering above normal when fast timing is not required and to change to fast timing when necessary such as upon rapid decreasing signals. The timing may be under direct control of the ripple in the output of a rectifier not affected by the improved results obtained to avoid degeneration. There is, thus, provided a system for automatically varying the filter and timing characteristic of a rectifier system which may be employed in any type of electrical current transmission system where such a high quality control is desired.

I claim as my invention:

1. In an electrical current transmission system, the combination of an alternating current signal source, means for rectifying said alternating current signal to obtain a unidirectional current whose amplitude corresponds to the variations in the peak value of the amplitude of said alternating current signal, and means for filtering said rectified current, said filtering means including impedance means and means for utilizing the ripple components of said unidirectional current for varying said impedance means, the timing, and the degree of filtering of said filter, said filtering means further including a condenser, a variable impedance in shunt with said condenser, and electronic means controlled by the amplitude of said ripple components for varying the amount of said impedance in shunt with said condenser.

2. In an electrical current transmission system, the combination of an alternating current signal source, means for rectifying said alternating current signal to obtain a unidirectional current whose amplitude corresponds to the variations in the peak value of the amplitude of said alternating current signal, and means for filtering said rectified current, said filtering means including impedance means and means for utilizing the ripple components of said unidirectional current for varying said impedance means, the timing, and the degree of filtering of said filter, said filtering means further including a condenser, a variable impedance in shunt with said condenser, and an electronic device on which said ripple components are impressed for changing said shunt impedance value and the discharge rate of said condenser to correspondingly change the timing of said filtering means.

3. In combination, a source of alternating current signal, a rectifier for rectifying said signal, a filter connected to the output of said rectifier, said filter including at least one timing

condenser and a variable shunting resistor, and means associated with said resistor for automatically varying the resistance thereof in accordance with the amplitude of the ripple components in the rectified current.

4. A combination in accordance with claim 3 in which said last mentioned means includes means for obtaining a voltage corresponding to the amplitude of the ripple components in the output of said rectified, and said resistor in shunt to said timing condenser is an electronic device, said voltage obtained from said ripple components varying the impedance of said electronic device.

5. In combination, a source of alternating current signal, a rectifier for rectifying said signal, a filter connected to the output of said rectifier, said filter including at least one timing condenser, and means associated with said condenser for automatically varying the discharge rate thereof in accordance with the nature of the signal being rectified, said last mentioned means including a second rectifier for said signal currents, a third rectifier for the ripple components from said second rectifier, and a variable impedance device, the output of said third rectifier being connected to the input of said impedance device for varying the rate of discharge of said timing condenser in accordance with the amplitude of the ripple components from said second rectifier.

6. A system for obtaining a unidirectional current corresponding to the peak value of the amplitude of an alternating current signal comprising means for rectifying said signal currents, a condenser and a variable impedance in shunt thereto for filtering said rectified current, said rectified current containing ripple components having an amplitude depending upon the nature of said signal and the effectiveness of said condenser and impedance filter, and means for utilizing said ripple components for varying the impedance in shunt to said condenser.

7. A system in accordance with claim 6 in which said variable impedance includes an electronic device in shunt to said condenser, and said last-mentioned means includes an automatic control circuit for rectifying said ripple components contained in said rectified current, said control circuit varying the impedance of said electronic device in accordance with the amplitude of the ripple present in said rectified current.

8. A system for obtaining a unidirectional current corresponding to the peak value of the amplitude of a signal current comprising a first rectifying means for said signal current, means for filtering the output of said rectifying means, a second rectifying means for said signal current, a second filtering means for the output of said second rectifying means, a variable impedance device connected in shunt to said first mentioned filtering means, and a third rectifying means for rectifying the ripple components present in the output of said second mentioned rectifying means, and means for connecting the output of said third rectifying means with said impedance device for varying the degree of filtering provided by said first mentioned filtering means.

9. A system in accordance with claim 8 in which said first mentioned filtering means includes a timing condenser, the discharge rate of which is varied by the output of said third rectifying means.

10. The method of automatically varying the timing and filtering characteristic of a rectifier-filter combination for an alternating current signal comprising rectifying said signal, filtering

said rectified signal through a condenser-variable impedance combination to a predetermined degree when said signal has a certain amplitude characteristic, and utilizing the ripple component in said rectified signal for varying the impedance value of said combination to vary the degree of filtering of said rectified signal in accordance with the variations in the amplitude characteristic of said signal.

11. The method of obtaining a unidirectional current corresponding to the peak value of the amplitude of a signal current comprising rectifying said signal current, filtering said rectified current through a condenser-variable impedance combination to a predetermined degree when said signal has a certain amplitude characteristic, and rectifying the ripple component in said rectified current for varying the impedance value of said combination in accordance with the rate of departure of said signal current from said certain amplitude characteristic.

12. The method of obtaining a unidirectional control current from an alternating current signal comprising rectifying said signal, filtering said rectified currents in an amount dependent upon the amplitude variation of said signal being rectified, rectifying the ripple components of said rectified currents, filtering said rectified ripple

components to a high degree, and utilizing said rectified and filtered ripple components for changing the degree of filtering of said rectified signal.

- 5 13. The method of obtaining a uni-directional control current from an alternating current signal comprising rectifying a portion of said signal to provide a first control current, filtering said first control current, rectifying another portion of said signal for obtaining a second control current, and further rectifying the ripple components of said second control current for obtaining a current for varying the amount of ripple components in said first control current.
- 10 14. The method of obtaining a uni-directional control current from an alternating current signal comprising rectifying a portion of said signal to provide a first control current, said control current having a certain amount of ripple components therein, filtering said first control current, rectifying another portion of said signal for obtaining a second control current, said second control current having a certain amount of ripple components therein, and controlling the 20 amplitude of the ripple components in said first control current by the ripple components in said second control current.
